CLAIM

The ornamental design for a crochet thread holder, as shown and described.

DESCRIPTION

FIG. 1 is a first perspective view of a first embodiment of a crochet thread holder showing my new design;

FIG. 2 is a second perspective view thereof;

FIG. 3 is a first plan view thereof;

FIG. 4 is a second plan view thereof;

FIG. 5 is a first side view thereof;

FIG. 6 is a second side view thereof;

FIG. 7 is a third side view thereof;

FIG. 8 is a forth side view thereof;

FIG. 9 is a first perspective view of a second embodiment of a crochet thread holder showing my new design;

FIG. 10 is a second perspective view thereof;

FIG. 11 is a first plan view thereof;

FIG. 12 is a second plan view thereof;

FIG. 13 is a first side view thereof;

FIG. 14 is a second side view thereof;

FIG. 15 is a third side view thereof; and,

FIG. 16 is a forth side view thereof.
